UNITED STATES PATENT OFFICE.

JOHN ROBERT DAVIS, OF WAKEFIELD STATION, ASSIGNOR OF ONE-HALF
TO C. E. CARTER, OF APPOMATTOX COUNTY, VIRGINIA.

BALE-TIE.

SPECIFICATION forming part of Letters Patent No. 378,874, dated March 6, 1888.

Application filed August 13, 1887. Serial No. 246,866. (No model.)

To all whom it may concern:

Be it known that I, JOHN ROBERT DAVIS, a citizen of the United States, residing at Wakefield Station, in the county of Sussex and State of Virginia, have invented certain new and useful Improvements in Bale-Ties; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The special object of the invention is to make a bale-tie coupling which may be easily fastened or unfastened, cheaply manufactured from metal, and less liable to get out of order.

Figure 1 of the drawings is a plan view of 20 my bale-tie coupling with its parts locked together; Fig. 2, a median longitudinal vertical section; Fig. 3, a perspective detail view of the male part of my coupling, and Fig. 4 a similar view of the female part.

25 In the drawings, A represents the male and B the female part of the bale-tie coupling, the former having the back a, which carries on the inside the projection a', with its tongues a² a³. The part A is also provided with the cross- 30 slot a⁴, and the part B with the cross-slot b⁴, to receive the ends of the bale-band, while part A has a sloping shoulder, a⁵, in front of the tongue a³, up which the end b⁵ of part B is pushed in order to unlock the coupling. The

part B has a cavity, b', to receive the projection a', the overhanging shelf b, to receive thereunder the tongue a², and a sloping shelf, b³, on which the tongue a³ finds a bearing.

In order to lock my coupling A B, the part A is pushed upon the part B, so that the tongue a² will slide upon the shelf b² and until the edge of the shelf b³ passes the front edge of the tongue a³, when the front edge, b⁵, of the part B drops behind the sloping shoulder a⁵ of part A. The operator now lets go the coupling A B, when the pressure of the baled cotton, hay, or other material automatically locks the parts and keeps them securely fastened together.

In order to unlock the parts A B, it is only necessary to push the part B on the part A and press on its rear end, when the bale-tie will be uncoupled.

Having thus described my invention, what I claim as new, and desire to protect by Letters Patent, is—

35 A bale-tie consisting of the male and female parts A B, having cross-slots a⁴ b⁴, the part A having the back a, carrying the inside projection, a', provided with tongues a² a³, and the part B having the cavity b' and shelves b² b³, as shown and described.

40 In testimony whereof I affix my signature in presence of two witnesses.

JOHN ROBERT DAVIS.
